DIP INK WELL

Filed Sept. 13, 1946

Fig. 2.

UNITED STATES PATENT OFFICE

2,547,100

DIP INKWELL

Raymond Spilman, Bronxville, N. Y., assignor to
 L. E. Waterman Company, New York, N. Y., a
 corporation of New York

Application September 13, 1946, Serial No. 696,844

2 Claims. (Cl. 120—59)

1

This invention relates to a container cap for a dip ink well. More particularly it relates to a reservoir type cap for use with a standard commercial ink bottle and is designed to replace the cap ordinarily carried by the bottle at the time of purchase. The invention further relates to a housing for the cap and container.

Generally speaking, the invention comprises, in combination, a container for ink having an opening through which the ink may pass, a dip well or reservoir type cap for the container, a base for supporting the cap and container in an inclined position, and a cover adapted to be secured to the base and to enclose the cap and container. The cover is provided with an aperture which opens into the dip well or reservoir of the cap and which may receive a pen holder. According to the invention the ink container, with the dip well cap attached thereto, is simply placed on its side for use, rather than inverted as is customary, and hence it rests in a stabler position. If desired, the cap and container may be used independently of the housing, as together they constitute a self-contained unit.

An object of the invention is to provide an ink container cap as above described. A further object is to provide a base and cover for enclosing the container and cap in a compact form, the cover incorporating a pen-supporting aperture. Other objects and advantages will appear herein-after.

The invention may be better understood by referring to the accompanying drawings in which a preferred embodiment is illustrated and in which:

Fig. 1 is a plan view looking down on the cover enclosing the assembled dip well cap and container;

Fig. 2 is a sectional view on the line 2—2 of Fig. 1;

Fig. 3 is a perspective view of the cap;

Fig. 4 is a perspective view of a closure for the ink bottle;

Fig. 5 is a perspective view of a commercial type ink bottle;

Fig. 6 is a fragmentary side view of the neck of the ink bottle of Fig. 5;

Fig. 7 is a side view partly in section of the closure of Fig. 4; and

Fig. 8 is a bottom view of the closure of Fig. 4.

In the drawings, 10 is a standard commercial type ink bottle or container. As shown, it is somewhat angular in shape and has flat sides, but it may have any generally suitable shape and sides. The container has a circular neck 11

in which is formed the opening 12. A circular closure 13 having a flange 14 is adapted to cover opening 12 as by gripping and partially overlying the neck, as shown in Fig. 2. The closure has an orifice 15 in the lower part thereof which is of a shape generally resembling an inverted key hole with the lower portion somewhat elliptical in outline (Fig. 4). A washer 16 is interposed between the top of neck 11 and the inner side of closure 13 and serves to prevent ink from leaking past the neck and closure.

A cap or head 17 of generally conical shape is secured to the closure, as by attachment to the flanged portion 14 through means of adhesive or solder or by a press fit. For practical purposes, the cap and closure may be considered as one piece to constitute a head, as the two may be joined together prior to being attached to the neck 11. The closure may thus be regarded as

10 a wall or end of the cap and, as shown, such wall is circular in shape and is provided with the flange 14. The cap has a hollow interior or dip well 18. An entrance 19 in the upper portion of the cap provides access to the dip well.

15 The cap 17, with the wall or closure 13 attached, may be secured or locked to the neck 11 by co-operating locking means disposed on the flanged wall and neck. Care must be had in attaching the wall or closure 13 to the cap 17 to locate

20 the orifice in such a position that its uppermost position is below the lowermost portion of entrance 19 in the cap, as shown in Fig. 2. The locking means on the neck 11 comprise threads, shown in the form of thread lengths 20, 21, each length being separated from the other and each having an engaging portion and a locking portion. In Figs. 5 and 6 are shown the engaging portion 22 of thread length 21 and the locking portion 23 of thread length 20. The locking

25 means on the flanged wall 14 of the cap comprise thread engaging members in the form of lugs 24, 25, as shown in Fig. 8. In applying the cap to the neck, the lugs are aligned with the spaces or slots, one of which is shown at 26, which

30 separate the thread lengths, and the cap is moved inwardly over the neck until the lugs come against the stop 27. Then the cap is twisted so that the lugs engage the thread lengths at the engaging portions of the latter. Lug 24, for example, will engage the thread engaging portion 22. The

35 cap is twisted about the neck until the lugs become locked in the locking portions of the thread lengths. Lug 25 (Fig. 8), for example, will be locked in the locking portion 23 (Fig. 5). The 40 lugs move in grooves 28, 29 (Fig. 6) formed in the

neck between the two thread lengths and the stop 27. At the locking portions of the thread lengths the grooves are more constricted than at the engaging portions.

As will be understood, the position of the lugs relative to the orifice in the flanged wall 13 of the cap is such that the orifice will invariably be located in its lowermost position relative to the ink level in the inclined container. It will also be understood that the closure 13, provided with the lugs above described, may first be secured to neck 11 in the manner set forth and that the cap 17 may thereafter be attached to it.

Means are provided for supporting the container and cap in an inclined position, preferably with the cap disposed below the container, and as shown, such means may be in the form of base 30 having a transverse rib 31 integral therewith. Base 30 is also provided with suitable lands or ledges 32, 33, and upstanding portions 34, 35. The portion 35 is hooked, as at 36, where it may engage the cap 17 along an edge of the entrance 19.

A cover or case 37 is adapted to be secured to base 30 and to enclose the container and cap therein. The lower portions 38 and 39 of cover 37 are suitably shaped to engage the lands 32, 33, and upstanding portions 34, 35, respectively, of base 30, forming a smooth compact housing for the cap and container. Cover 37 has an aperture 40 therein which opens into the dip well 18 of cap 17 and which also is adapted to receive a pen holder and nib, as indicated at 41. A shoulder 42 near the base of the aperture serves to support the pen holder while the nib is immersed in ink 43.

In assembling the ink container in the housing, the cap which ordinarily comes with the ink container is removed and replaced by the cap of this invention. As described above, the new cap may be regarded as having the closure 13 as an integral part thereof. Upon covering or enclosing the container neck with the cap in the manner described, it is possible to place the container on its side in base 30 without danger of losing ink 43 through overflow from entrance 19 in the cap. This will be apparent when it is considered that ink 44 from container 10 will flow through orifice 15 to dip well 18 only so long as air may enter the container through the orifice. When the ink level in the dip well rises above the uppermost portion of the orifice, the flow of air to container 10 will cease, and thereafter the atmospheric pressure on the ink in dip well 18 will counterbalance the combined pressures of the air and the ink head in container 10. The ink levels in container 10 and dip well 18, at the time when the pressures have become equal, will be substantially as shown in Fig. 2. In this connection, it was found that with the general inverted keyhole shape of the orifice, the lower portion having a generally elliptical contour, the gurgling and/or bubbling effect otherwise incident to the flow of ink from the container to the dip well was avoided.

With the cap and container in position in base 30, cover 37 may be easily pushed into place, and the device is ready for use. It should be noted that base 30 has a fairly large volume such that in case of ink leaks through breakage or other

accidents, it will retain all the ink which may have been present in the container. Base 30 may conveniently be made of metal, such as aluminum, but may also be made of plastic or other desirable material, as may cover 31.

It will be understood that the invention as described represents a preferred embodiment and that the invention is capable of various modifications within the scope thereof.

In the light of the foregoing description, the following is claimed:

1. In a device of the character described, in combination, a container for ink having a neck through which said ink may pass, a hollow removable cap for said container, a base for supporting said container and cap in an inclined position with the cap disposed below the container, said base having means for engaging the cap, said cap having a flanged wall adapted to be locked to said neck, said cap having an entrance in an upper portion thereof, said flanged wall having an orifice through which ink may pass from said container to the lower portion of said cap opposite said entrance, cooperating means on said flanged wall and said neck for invariably locating said orifice in its lowermost position relative to the ink level in the container, thereby permitting the pressures on each side of the orifice to counterbalance each other before the ink in said cap overflows through said entrance, and a cover member engageable with the base to form a housing for the cap and container, said cover member having an aperture aligned with the entrance in the cap.
2. In a device of the character described, in combination, a container for ink having a neck through which ink may pass, a hollow removable head for said container, a base for supporting said container and head in an inclined position with the head disposed below the container, said head having a flanged wall adapted to grip and enclose said neck, said head having an entrance in an upper portion thereof, said flanged wall having an orifice through which ink may pass from said container to the lower portion of said head opposite said entrance, cooperating means on said flanged wall and said neck for invariably locating said orifice in its lowermost position relative to the ink level in the container, said cooperating means comprising a thread-engaging member on said flanged wall, and threads on said neck, and a cover member engageable with the base to form a housing for the head and container, said cover member having an aperture aligned with the entrance in the head.
